FLOATING CORNER CONSTRUCTION

George William Anderson, Port Washington,
N. Y., assignor to United States Plywood Cor-
poration, New York, N. Y., a corporation of
New York

Application September 23, 1944, Serial No. 555,428

1 Claim. (Cl. 20—4)

1

This invention relates to the construction of wall panels and particularly to the corner panels.

Heretofore it has been found that the corners of panel walls become marred or separated due to expansion and contraction by temperature changes. The paint is also sometimes injured so that the appearance of the walls becomes unsightly. Similar troubles arise when the panels shrink after being installed.

Attempts to remedy these defects have not been entirely satisfactory due to the increased expense and to the fact that devices installed to prevent such defects are visible at least in part and mar the appearance of the paneling.

With the present invention wall paneling can be installed having either inside or outside corners, or both, in such a way that no cracks appear at the corners and no injury to the appearance of walls at inside or outside corners takes place and no part of the devices for accomplishing this is visible to the occupants of the room.

In carrying out the invention contacting edges of the panels at corners are securely connected together by devices located entirely on the back side of the panels at the corners in such a way that the adjacent edges are prevented from moving with respect to each other so that wall paper is not torn and no paint lines become visible. In this way floating corners of the panel wall are provided since they are not connected to the studding and are therefore free to move or float due to expansion and contraction of the panels. At the same time the panels cannot separate or move with respect to each other at the corners.

The invention may be understood from the description in connection with the accompanying drawing, in which Figure 1 is a side view partly in section showing an illustrated embodiment of the invention;

Figs. 2 and 3 are perspective views on an enlarged scale showing some of the details;

Fig. 4 is a section through line 4—4 of Fig. 3.

In the drawings, reference characters 1 and 2 indicate inside corner studding, and reference characters 3 and 4 indicate side studding resting on sills 5 and 6. Furring strips 7 and 8 are applied along the inner edges of the studding 3 and 4.

The inside edges of the sills 5 and 6 are scarfed, as indicated at 9 and 10 from near the corner for some distance therefrom. A distance of about 15 to 20 inches is usually sufficient. This scarfing is sufficiently deep to compensate for expansion and contraction of the paneling.

2

Panels 11 and 12 meet at an inside corner of a room near the studding 1 and 2.

Wood strips 15 and 16, such as fir plywood, for example, are glued to the paneling 11 and 12, respectively, near their edges with the panel 11 overlapping the edge of the panel 12 so that the edge of the strip 15 overlaps the edge of the paneling 12 and lies against the outside of the paneling 11 while the strip 16 lies against the outer side of the paneling 12 and the edge of paneling 11.

The strips 15 and 16 are securely attached to the paneling 11 and 12, respectively, such as by gluing the same thereto. Before these strips 15 and 16 are glued to the paneling 11 and 12, they are provided with interlocking catches or holding members 17 and 18, for example, Figs. 3 and 4. Screws 19 and 20 hold these catches securely in slots that are provided across the strips 15 and 20 16 to receive them. Also, the ends 21 and 22 of these catches are preferably bent at right angles to lie flat against the edges of the strips 15 and 16. A number of such catches are attached to each strip 15 or 16 and the catches are all alike. 25 The slots 23 and 24 in which the catches 17 and 18 are placed are of such size that the outer surfaces of the catches are flush with the surfaces of the strips 15 and 16 when the catches are in place. The catches are provided with interlocking projections 25 and 26 with scarfed ends 27 and 28.

In carrying out the invention the scarfed parts 9 and 10 are provided at the corners extending about fifteen or twenty inches from the corners 35 or farther where the widths of the walls or temperature changes are such that contraction and expansion is greater. The edges of the panels 11 and 12 that are to be in a corner have strips 15 and 16 attached thereto as by gluing the same in place to the outer surfaces of the panels with the catches 17 and 18 extending beyond the edges of the panels. The projections 25 and 26 are interlocked whereupon the edges of the panels 11 and 12 are held securely in place as indicated 40 in Figs. 1 and 3 so that they do not move with respect to each other even when extreme expansions and contractions take place.

It will be obvious that when the strips 15 and 16 are fastened together by the catches 17 and 18 they are securely and rigidly held together, and since these strips are secured to the panels 11 and 12, these panels are held securely together so that when expansion and contraction takes place there is no relative displacement between 55 the edges of the panels 11 and 12 so that it is im-

possible for openings or cracks to appear at the corner and the paint or wall paper or such at the corner cannot be marred because of expansion and contraction of the panel.

It has been found to be advantageous to make the paneling 11 and 12 of thin sheets or layers of wood glued together with grain of alternating layers of wood at right angles because this minimizes expansion and contraction to about one quarter to three-eighths of an inch per twelve feet of width of wall so that the beveling 9 and 10 does not have to be very deep. The edges of the panels of plywood and portion between the edges are glued to the faces of the furring strips such as 7 and 8.

What is claimed is:

In a housing construction, a wall panel, a second wall panel, cooperating catch means attached to each of said panels so that upon expansion and contraction of the panels, the edges of said panels will be able to move only as a unit, 20 a frame comprising studs and sills supporting

said panels, a portion of said sills, adjacent said panels, being scarf'd from a corner of said frame for a short distance toward the adjacent corners whereby space will be provided between said sills and said panels for the edges of said panels to float.
